FILING MACHINE

Benjamin Grob, Grafton, Wis.

Application January 30, 1943, Serial No. 474,083

15 Claims. (Cl. 29—76)

This invention relates to filing or abrading machines of the continuous motion type.

Machines of the type referred to are now extensively used throughout the metal working arts to give a desired contour and or finish to parts of various metal objects. Such machines ordinarily involve a longitudinal succession of rigid filing or abrasive elements attached to a continuously driven endless carrier by which they are advanced past or through a piece of work, the filing or abrading action being effected by pressing the piece of work against the rigid elements as they are thus mechanically advanced.

There are kinds of work however for which such machines, as heretofore designed, are not adapted or capable of use. That is to say, in some instances, the size or shape of the work piece, or the peculiar location thereon of the part to be filed or abraded, renders the same inaccessible to the moving files or abrasive elements of such machine.

An object of the present invention is to provide a filing or abrasive machine of the continuous motion type so constructed as to render the filing or abrasive elements more readily accessible to the work at hand.

Another object is to provide an endless file carrier for filing and abrasive machines of the type mentioned capable of following paths of maximum deflection.

Another object is to provide an endless file carrier for filing and abrasive machines of the type mentioned so constructed as to permit mounting the filing or abrasive elements on the back or inner side of the carrier.

Other more specific objects and advantages will appear, expressed or implied, from the following description of an illustrative embodiment of the present invention.

For purposes of illustration and explanation the invention is herein shown as embodied in a machine specially designed to file the rear marginal surfaces of turbine vanes, although the same may be advantageously utilized in filing and abrading machines for various other kinds of work.

In the accompanying drawings—

Figure 1 is a horizontal sectional view, taken substantially along the line 1—1 of Fig. 2, of a filing machine constructed in accordance with the present invention.

Fig. 2 is a vertical sectional view on a larger scale, taken substantially along the line 2—2 of Fig. 1.

Fig. 3 is a vertical sectional view on the same 55

scale as Fig. 2, taken substantially along the lines 3—3 of Figs. 1 and 2.

Fig. 4 is an enlarged, fragmentary, horizontal sectional view, illustrating the course of the file chain during a filing operation.

Fig. 5 is an inner face view, partly in section, of the file chain shown in the other views.

Figs. 6 and 7 are fragmentary, top plan views of the work piece illustrating the method of indexing the same.

The filing and abrading machine selected for illustration is shown arranged to file the rear marginal faces of the successive vanes *a* of a turbine wheel *b*. These vanes, which project radially from the periphery of the wheel, are of substantially concavo-convex contour and arranged in close succession so that the curved spaces therebetween are rather narrow and difficult of entry.

As originally formed the several vanes *a* terminate in edges *c* of substantial though narrow width, as best shown in Figs. 4, 6 and 7, but in order to effect efficient turbine operation it is necessary that these edges be reduced to knife edge form, such as indicated at *c'* in Fig. 4, this being accomplished by filing away the rear marginal face *d*, at each side of each vane, in such manner as to leave marginal faces *d'* disposed at a predetermined angle with respect to the plane 20 of rotation of the turbine wheel.

This filing operation on the rear marginal faces of each vane was heretofore laboriously performed by hand. But by the use of the machine herein shown, this filing operation is now mechanically 25 performed with great saving in time and cost.

The machine shown comprises a suitably supported stationary table 10, and a hollow head section 11, supported above and by the table 10 through an open rectangular column 12.

A vertically disposed disk 13, fixed to the front face of a vertical mounting plate 14, is provided with a peripheral flange 15 which forms a seat for the periphery of the turbine wheel *b*, which in this instance constitutes the work piece. The turbine wheel *b* is shown centered and supported by a hollow cylindrical bushing 16, carried by the center of the disk 13 and projecting horizontally therethrough into a central opening *e* with which the turbine wheel is provided, the opening *e* being 45 of a size to provide a close rotating fit on the bushing 16.

The turbine wheel *b* is removably retained on the bushing 16 and against the flanged disk 13 by appropriate means, such as a shouldered disk 17 removably seated in the opening *e* of the tur-

bine wheel and yieldably retained in place by a spring urged rod 18 which extends through the disk 17 and bushing 16 and which is provided at its rear end with a head 19 slidably fitted in an end 20 of a cylindrical housing 21. The housing 21 is shown fixed to and projecting from the rear face of the mounting plate 14. Nuts 22 on the forward end of the rod 18 bear against the shouldered disk 17, and a compression spring 23 within the housing 21 acts against the head 19 of the rod, so that the latter, acting through the nuts 22, yieldably retains the shouldered disk 17 and turbine wheel b in the position shown in Fig. 3.

The rod 18 may be advanced against the thrust of the spring 23 to release the disk 17 and turbine wheel b, suitable mechanism being provided for the purpose. In this instance such mechanism includes a vertical shaft 24 rotatable in the end of the housing 21 and provided at one side with a recess 25 which normally clears the head 19 of the rod 18. Shaft 24 is provided with an appropriate operating lever 26 which extends forwardly to a point within convenient reach of the operator and which may be swung to rotate the shaft 24 and thus force the rod 18 forwardly by a cam action. With the rod 18 thus advanced, the disk 17 may be removed therefrom, the disk having a radial slot 27 for that purpose, and after removal of the disk 17, the turbine wheel b may be readily withdrawn from its supporting bushing 16.

The turbine wheel b is normally locked against rotation by means which also functions as an indexing mechanism therefor. The mechanism herein shown for that purpose comprises a vertical shaft 28 disposed above the center of the turbine wheel b and journalled in a pair of vertically spaced bosses 29 formed integral with and projecting forwardly from the vertical mounting plate 14. The shaft 28 carries a driving pinion 30 fixed thereto and closely confined between the bosses 29 coacting with the latter to prevent lengthwise movement of the shaft relative to the turbine wheel b. The central axis of the shaft 28 is disposed radially of the turbine wheel but preferably slightly offset laterally from the central plane of the turbine wheel for a purpose which will hereinafter appear.

The shaft 28 carries at its lower end a pair of diametrically disposed downwardly projecting cylindrical lugs 31 arranged to coact with a series of rectangular lugs f with which the turbine wheel shown is equipped. In this instance each of the turbine vanes a carries one of the lugs f, each projecting radially from a central portion of a vane end. The pair of lugs 31 on the shaft end normally loosely straddle a vane lug f and contact the opposed faces of adjacent vane lugs f, as shown particularly in Fig. 6, to temporarily lock the turbine wheel against rotating.

The arrangement is such however that by rotating the shaft 28 in a clockwise direction, as indicated by the arrow in Fig. 7, one of the shaft lugs 31 engages what was the straddled vane lug f and advances that lug and the turbine wheel toward the right a distance equal to the center-point spacing between vanes; and during this shaft rotation, the other shaft lug 31 swings clear of the former straddled vane lug f and ultimately engages the leading face of an advancing vane lug to again temporarily lock the turbine wheel against further advance. The fact that the axis of the lug-carrying shaft 28 is laterally offset from the central plane of the turbine wheel, as hereinabove pointed out and as indicated in Figs. 6 and 7, makes it possible for one of the shaft lugs

31 to swing clear of the former straddled lug f during each advance of the turbine wheel in the manner above described.

The locking and indexing shaft 28 may be intermittently rotated through exactly one hundred and eighty degrees in the manner above described by any appropriate means, but that herein shown has proven entirely satisfactory. In this instance the shaft 28 is driven by the pinion 30 hereinabove mentioned, which is in constant mesh with a driving gear 32 twice its diameter and intermittently driven through exactly ninety degrees by a well known type of Geneva movement, best shown in Figs. 1 and 3. This movement includes a conventional radially slotted star wheel 33 and coacting mutilated disk 34 and driving pin 35. A vertical shaft 36 journalled in the head section 11 of the machine carries the gear 32 and star wheel 33, both fixed thereto. The mutilated disk 34 and driving pin 35 are fixed to a conventional crank arm 36' fixed to and driven by a vertical shaft 37. For a purpose which will later appear the shaft 37 extends upwardly from the table 10 through the head section 11. It is supported by a thrust bearing 38 and is continuously driven by any appropriate means (not shown).

Through the mechanism just described the locking and indexing shaft 28 is driven through one hundred and eighty degrees during each complete rotation of the shaft 37, each such rotation of the shaft 28 being completed within a brief time interval much shorter than the intervening periods of rest thereof.

During the filing of each turbine vane a, the turbine wheel remains in the lower position shown in Figs. 2 and 3 and, after completion of each such filing operation, the turbine wheel is elevated to clear the filing mechanism below it, indexed in the manner above described to bring the next vane into position, and thereafter again lowered to position said newly positioned vane within the range of operation of the filing mechanism. For this purpose the mounting plate 14 carrying the turbine wheel, shaft 28 and pinion 30, is vertically movable along a vertical shaft or column 39. In this instance the column 39 extends upwardly from the table 10 to and through the head section 11, and the mounting plate 14 is provided with rearwardly projecting upper and lower mounting ears 40 through which the column 39 extends and with which the latter has a close sliding fit. To retain the mounting plate 14 against swinging about the column 39, the plate is provided with a forked extension 41 which embraces a vertical guide rod 42 provided in the head section 11. A stop collar 43 adjustably fixed on the column 39 beneath the lower mounting ear 40 supports the mounting table in the lower position shown.

Provision is made for automatically raising and lowering the mounting plate 14 at predetermined intervals, the mechanism shown for that purpose comprising a horizontal disk 44, fixed to and rotatable with the shaft 37, and carrying an upstanding peripheral cam portion 45 which coacts with a roller 46 carried by a horizontal stud 46' projecting rearwardly from the mounting plate 14. The arrangement is such that, as the cam 45 rotates with the shaft 37 it engages beneath the roller 46 and lifts the mounting plate 14 to an elevation, as indicated in dotted lines in Fig. 3, where it is held during indexing movement of the turbine wheel, after which the cam 45 passes from beneath the roller 46, permitting

the mounting plate 14 to return to the lower position shown.

The filing mechanism shown comprises a drum 47 journaled upon a vertical spindle 48 fixed to and projecting upwardly from the table 10. The periphery of the drum 47 is preferably provided with a covering 49 of rubber or the like to afford a good driving surface for the file chain to be later described. In this instance the drum 47 is continuously driven by appropriate means, including a pulley 50 carried by the lower end thereof, pulley 50 being belt driven from a small pulley 51 which in turn rotates with a large pulley 52 belt driven from a small pulley 53, and which in turn is driven from an electric motor 54 through a belt 55 and large pulley 56 which rotates with pulley 53.

The filing mechanism also includes a continuous file chain preferably such as will now be described. As best shown in Figs. 4 and 5, the file chain is of wide flat form having relatively short, closely articulated inner and outer links 57 and 58 along each edge thereof, each of said links at one edge of the chain being rigidly connected with corresponding links at the other edge thereof through transverse bars 59 and 60, respectively. In fact, each transverse bar 60 is transversely bent at its opposite ends to form the outer links 58 and each transverse bar 59 is similarly bent to form the inner links 57. Each outer link 58 at one edge of the chain is hingedly connected to the adjacent inner links 57 by pins 61, which extend from one edge of the chain to the other and which provide hinged connections between the corresponding links at the other edge of the chain. The several pins 61 are retained by appropriate means, such as wire keys 62. The construction thus described results in a chain having an unusually high degree of flexibility in one direction—namely, about the closely spaced hinge pins 61, and one offering an unusually high resistance to bending, warping or twisting in any other direction.

The file chain shown also includes a series of rigid transversely extending filing elements 63 arranged on the inner face of the chain and projecting beyond the edges thereof. The projecting ends of the several filing elements adjacent one edge of the file chain are cut to provide conventional toothed filing faces 64. In this instance each filing element is securely anchored to one of the chain bars 59 by appropriate means such as screws 65.

As shown particularly in Figs. 1 and 2, the endless file chain is trained about the driving drum 47 and about a vertical positioning pintle 66, carried by a shaft 67 journaled in an appropriate hollow support 68 fixed to the table 10. The pintle 66 is horizontally offset from the drum and positioned immediately below the turbine wheel b, adjacent the vanes thereof, so that those upwardly projecting ends of the filing elements 63 having the filing faces 64 pass between successive turbine vanes a as they are carried by the filing chain about the pintle. The filing elements 63 being carried by the inner face of the chain, engage the rubber covering 49 on the drum 47 and also the face of the pintle 66 as they advance with the chain in the direction indicated by the arrows in Fig. 4.

The file chain is preferably tensioned by an idler roller 69, best shown in Fig. 4, which bears against the inner face thereof and which is carried by and between a pair of vertically spaced arms 70 and 71 carried by a hub 72 to form a

lever structure rockably supported upon a vertical stud 73 projecting from the table 10. A spring 74 urges the arms 70 and 71 and roller 69 in a direction to maintain the file chain in a taut condition. It will be noted from Fig. 4 that the roller 69 coacts with that stretch of the file chain which is approaching the turbine vanes a and that it so positions that portion of the file chain that the several filing elements enter between successive vanes without contacting either of them. This portion of the file chain is preferably further guided by an appropriate guide plate 75, carried by the table 10 and bearing against the rear faces of the lower ends of the filing elements as the latter approach the turbine vanes.

That stretch of the file chain which has passed about the positioning pintle 66 is so guided and controlled as to effect the desired filing action upon the rear marginal face of the adjacent turbine vane. For this purpose a pressure shoe 76 is provided having an end face 77 arranged to contact the rear faces of the upwardly projecting ends of the filing elements and to force them and particularly the filing faces 64 thereof into filing engagement with the adjacent turbine vane. In this instance the shoe 76 is mounted on an appropriate carrier 78 which is swingable about a vertical supporting stud 79 fixed to the table 10. The stud 79 is preferably disposed remote from the shoe 76 and with its axis substantially within the plane of the filing action, so that the slight advance of the pressure shoe 76 against the files is substantially a rectilinear motion.

In the machine shown the shoe 76 is advanced against the files by a spring 80 (Fig. 1) connected to the carrier 78 and table 10, and a stop screw 81 on the carrier coacts with a block 82 on the table 10 to limit the advance of the shoe 76. The extent or depth of the filing action may thus be regulated by adjustment of the stop screw 81.

Retraction of the shoe 76 from the file chain may be effected in various ways but the mechanism shown for that purpose has proven satisfactory. This mechanism, best shown in Fig. 1, includes a link 83 connected to the carrier 78 at a point beyond its supporting stud 79 and operatively engaged with a lever 84 supported on a vertical stud 84' on the table 10. The lever 84 is actuated by an appropriate cam 85 fixed to and driven by the shaft 37 hereinabove mentioned. The connection between the link 83 and lever 84 is preferably adjustable and for that purpose an element 86 is preferably provided, this element being swingable about the stud 79 and having a screw 87 engageable with the lever 84 and adjustable to regulate the angular relation between the lever and element, the link 83 being connected with the element 86.

The arrangement is such that when the high portion of the cam 85 engages the lever 84 the latter is actuated to operate the link 83 and thereby swing the carrier 78 against the action of the spring 80 in such direction as to retract the shoe 76 from the file chain.

It will be noted that the cam 85 as well as the cam 45, hereinabove mentioned, are carried and driven by the same shaft 37, so that the lifting, indexing and lowering of the turbine wheel and each filing operation on successive vanes thereof are carried out in definite timed relation, the shoe 76 being advanced by the spring 80, immediately after the turbine wheel has been lowered into the range of operation of the filing elements, and the shoe 76 being retracted by the cam 85

and link 83 prior to each lifting of the turbine wheel.

It is highly desirable, at the end of each filing operation, to withdraw the train of filing elements away from the vane face on which they have been acting in order that they may clear the vanes prior to each lifting of the turbine wheel. This is accomplished in this instance by the use of a vertical roller 88 (Figs. 1 and 4) which is carried by an arm 89 on the end of the carrier 78 in position to engage the inner face of the file chain and deflect the latter outwardly whenever the carrier 78 is swung to retract the shoe 76.

Due to the high flexibility of the file chain, the individual filing elements 63 are liable to twist or turn out of position in a manner to interfere with their proper entry between successive turbine vanes, with their proper passage about the pintle 66, and or with their filing function. To prevent this objectionable condition each file carrying bar 59 of the file chain is provided at its opposite ends with laterally projecting arms 90 which are formed integral with the links 57 and which have heads 91 at their outer ends which abut those of adjacent arms in a manner to hold the several bars 59 and filing elements 63 against twisting or turning during the straight line courses of the file chain as the latter approaches the pintle 66 and as it passes beyond the pintle. Also the outer links 58 of the file chain are provided with lugs 92 which project between successive file elements 63 to properly position the latter during their passage about the pintle 66.

Various changes may be made in the embodiment of the invention hereinabove specifically described without departing from or sacrificing the advantages of the invention as defined in the appended claims.

I claim:

1. A machine of the character described having an endless succession of substantially flat transversely extended filing elements or the like, an endless carrier for advancing said succession of elements edgewise along a predetermined path, said elements having end portions with abrasive faces projecting laterally beyond an edge of said carrier and means for supporting a work piece within the range of operation of said projecting end portions to be acted on by said abrasive faces.

2. A machine of the character described having an endless carrier, a succession of filing elements or the like extending crosswise of said carrier and having end portions with abrasive faces projecting laterally beyond an edge of said carrier, means for actuating said carrier, and means for supporting a work piece within the range of operation of said projecting end portions to be acted on by said abrasive faces.

3. A machine of the character described having a flexible nontwistable substantially wide flat endless carrier, a succession of filing elements or the like on said carrier, said elements being disposed transversely of said carrier and projecting laterally beyond an edge thereof, said projecting elements having abrasive faces, means for supporting and actuating said carrier to advance the projecting portions of said elements edgewise along a predetermined path, and means for supporting a work piece within the range of operation of said projecting portions to be acted on by said abrasive faces.

4. A machine of the character described having a flexible substantially wide flat endless chain, a succession of filing elements or the like

on said chain, said elements being disposed transversely of said chain and projecting laterally beyond an edge thereof, said projecting elements having abrasive faces, means for supporting and actuating said chain to advance the projecting portions of said elements along a predetermined path, and means for supporting a work piece within the range of operation of said projecting portions to be acted on by said abrasive faces.

10 5. A machine of the character described comprising a driving drum, a pintle laterally offset from said drum and disposed substantially parallel to the axis of the latter, an endless carrier trained about said drum and pintle, and a series of filing elements or the like on said carrier, said elements extending transversely of said carrier and having portions projecting beyond an edge of the latter and beyond the end of said pintle, and means for supporting a work piece adjacent but beyond said end of said pintle in position to be acted on by the projecting portions of said elements.

15 25 6. A machine of the character described having a pintle, an endless carrier mounted to travel along a path deflected by said pintle, and a series of filing elements or the like on said carrier, said elements extending transversely of said carrier and having portions projecting beyond an edge of the latter and beyond the end of said pintle, said projecting portions having abrasive faces, and means supporting a work piece adjacent but beyond said end of said pintle to be acted on by said abrasive faces.

30 35 7. A machine of the character described having an endless succession of transversely extended filing elements or the like, an endless carrier for advancing said succession of elements edgewise along a predetermined path, said elements having end portions with abrasive faces projecting beyond an edge of said carrier in position to act on a piece of work, and means for effecting a relative feed movement between said end portions and the piece of work to effect pressure 40 45 engagement of said abrasive faces against the work.

8. A machine of the character described having an endless succession of transversely extended filing elements or the like, an endless carrier for advancing said succession of elements edgewise along a predetermined path, said elements having end portions with abrasive faces projecting beyond an edge of said carrier in position to act on a piece of work, and means for forcing said 50 55 abrasive faces into pressure contact with the work.

9. In a machine of the character described for treating a recessed work piece, said machine having an endless succession of transversely extended filing elements or the like having end portions with abrasive faces arranged to project into the recess of the work piece, and means for advancing said elements edgewise along a predetermined path to cause said end portions to traverse said recess with said abrasive faces against a side wall of the latter.

10. In a machine of the character described for treating a recessed work piece, said machine having a flexible endless carrier, a succession of filing elements or the like on said carrier, said elements extending transversely of said carrier and having end portions with abrasive faces arranged to project into the recess of the work piece, means including a narrow element positioned to flex said carrier to position the latter

adjacent said recess, and means for driving said carrier to cause the projecting end portions of said elements to traverse the recess in the work piece with said abrasive faces in contact with a side wall of said recess.

11. In a machine of the character described the combination of an endless succession of transversely extended filing elements or the like having projecting end portions, means for advancing said succession of elements along a predetermined path, a work support, means for shifting said work support to shift the work into and out of the zone of operation of said projecting end portions, and means for indexing the work while out of said zone of operation.

12. In a machine of the character described the combination of a flexible endless carrier, driving means therefor, a succession of filing elements carried by said carrier, said elements extending transversely beyond an edge of said carrier and having abrasive faces, a narrow element coacting with said carrier to deflect and position the same relative to a work piece, means coacting with said carrier to determine the course of travel thereof as it approaches said last named element, and means coacting with said carrier to determine the course of travel thereof as it moves from said last named element.

13. An endless chain for machines of the character described, said chain comprising a plurality of widely spaced series of relatively short links, hinge connections between successive links of each

series, a series of transverse bars each rigidly connecting one link of one series with a corresponding link of another series to form a rigid structure swingable about said hinge connections, and a succession of transversely disposed filing elements or the like fixed to said bars.

14. An endless chain for machines of the character described, said chain comprising two widely spaced series of relatively short hingedly connected links, each series comprising alternate inner and outer links, a series of transverse bars each rigidly connecting each link of one series with a corresponding link of the other series to form rigid units, and a succession of transverse filing elements or the like carried by said bars.

15. An endless chain for machines of the character described, said chain comprising two widely spaced series of links, a line of transverse pins forming hinge connections between successive links, each series of links comprising inner and outer links, a succession of transverse bars each rigidly connecting one inner link of one series with an inner link of the other series, a second succession of transverse bars each connecting one outer link of one series with an outer link of the other series, said first and second named succession of bars being disposed at opposite sides of said line of pins, and a succession of transverse filing elements or the like respectively fixed to the bars of one series.

BENJAMIN GROB.
